DESIGN FOR A CLOCK DIAL OR SIMILAR ARTICLE

Harley G. Thompson, San Francisco, Calif.

Application September 14, 1944, Serial No. 115,299

Term of patent 7 years

(Cl. D42—10)

To all whom it may concern:

Be it known that I, Harley G. Thompson, a citizen of the United States of America, residing at San Francisco, in the county of San Francisco and State of California, have invented a new, original, and ornamental Design for a Clock Dial or Similar Article, of which the following is a specification, reference being had to the accompanying drawing, forming a part thereof.

The figure is a face view of a clock dial or similar article showing my new design, which is of no appreciable thickness.

I claim:

The ornamental design for a clock dial or similar article, substantially as shown and described.

HARLEY G. THOMPSON.
